(57) **CLAIM**

The ornamental design for a cookware vessel, as shown and described.

DESCRIPTION

FIG. 1 is a top, a front, and side perspective view of the claimed design in its environment;

FIG. 2 is a front view of the claimed design;

FIG. 3 is a rear view of the claimed design;

FIG. 4 is a left side view of the claimed design;

FIG. 5 is a right side view of the claimed design;

FIG. 6 is a top plan view of the claimed design; and,

FIG. 7 is a bottom plan view of the claimed design.

The ornamental design which is claimed is shown in solid lines in the drawings. The broken lines in the drawings are for illustrative purposes only and form no part of the claimed design.
